Geo. C. Raymond.

UNITED STATES PATENT OFFICE.

CHARLES H. TRYON, OF SYRACUSE, NEW YORK.

STOVE-PIPE THIMBLE.

SPECIFICATION forming part of Letters Patent No. 374,643, dated December 13, 1887.

Application filed October 16, 1886. Serial No. 216,389. (No model.)

To all whom it may concern:

Be it known that I, CHARLES H. TRYON, of Syracuse, county of Onondaga, in the State of New York, a citizen of the United States, have 5 invented certain new and useful Improvements in Stove-Pipe Thimbles, of which the following is a specification.

My invention relates to an improvement in stove-pipe thimbles and method of manufacturing the same. The object is to provide a thimble which shall be more durable and convenient than those hitherto manufactured, and which can be furnished at a reduced cost.

With these ends in view my invention consists in first forming adjusting-hooks of wire, and subsequently casting the end rings of the thimble around the ends of the adjusting-hooks.

My invention further consists in the means and method more fully described hereinafter, and pointed out in the claims.

In the accompanying drawings, Figure 1 is an isometric view of the thimble. Fig. 2 is a vertical section taken through line $x x$ of Fig. 1. Fig. 3 is a plan view of the inner face of 25 one of the ends of the thimble, and Figs. 4, 5, 6, and 7 are views in detail.

A and B represent the ring-shaped ends of the thimble, each of which is provided with an annular flange, a , on its side toward the opposite end. At points a suitable distance apart, preferably at two diametrically opposite points, each of the flanges is re-enforced, as shown at C, forming bosses for more securely supporting the adjusting-hooks D. These 35 hooks D are formed of a good quality of wire, and are set in the molds in which the rings A B are cast in positions to occupy the centers of the bosses C. The metal for the ends A and B is then cast into the molds around the ends 40 of the hooks D, and when cool hold them in position as though a part of themselves. One of these ends—B, for example—is provided with a tubular section, F, one end of which fits around the outer face of the flange a outside of the hooks D, and the opposite end is adapted to telescope within the open end of a similar tubular section, F, secured to the end A around its flange a .

To avoid the labor and expense of riveting or bolting the tubular sections F to the ends, 50 I find it expedient to solder them to the stems of the hooks D.

The ends A and B, when adjusted with their respective tubular sections F in the opposite ends of a stove-pipe hole, are drawn toward 55 each other and held in the desired adjustment by means of a pair of spiral springs, E, provided with eyes at their opposite ends adapted to slip over the curved ends b of the hooks D.

By the above-described method I am enabled 60 to provide strong, light, and durable hooks in the place of the old cast-metal lugs or hooks and without any labor of drilling or riveting the hooks to the ends, and my tubular sections are also secured in a simple and economical 65 manner, thus rendering the entire cost of manufacturing much less than heretofore, and at the same time producing a better, or equally as good, product.

Having thus described my invention, what I 70 claim as new, and desire to secure by Letters Patent, is—

1. The herein-described stove-pipe thimble, consisting, essentially, of the cast-metal ring-shaped ends having adjusting-hooks cast therein, the tubular telescopic sections or casing soldered to said adjusting-hooks, whereby they are secured to said ends, and the springs engaging the adjusting-hooks, substantially as described.

2. In a stove-pipe thimble, the combination of the cast-metal ring-shaped ends, the annular flanges a , cast integral with said ring-shaped ends, the wire adjusting-hooks cast in said ring-shaped ends, the telescopic sections F, adapted 75 to engage the outer faces of said flanges a and be attached to said ring-shaped ends by being soldered to said adjusting-hooks and the springs engaging said hooks, substantially as described.

In witness whereof I have hereunto set my 85 hand this 11th day of October, 1886.

CHARLES H. TRYON.

In presence of—

W.M. BOON,

THEO. G. ROBINSON.
